UNITED STATES PATENT OFFICE

ROBERT O. WOOD, OF HAMBURG, NEW YORK, ASSIGNOR TO NATIONAL ANILINE & CHEMICAL COMPANY, INC., OF NEW YORK, N. Y., A CORPORATION OF NEW YORK

PREPARING DYE PASTE FOR PRINTING AND DYEING

Application filed August 26, 1929. Serial No. 388,526.

This invention relates to the production of smooth dye pastes, free from lumps and grit or other foreign matter, to be used for printing and dyeing.

5 In the printing of designs on fabrics, the dye is applied by means of a copper roll, in the surface of which is engraved the design to be printed on the cloth. This roll is smooth and polished, except where the de-
pressions of the engraving occur.

10 In operation, the surface of the roll is completely coated with the dye paste mixed with a thickening agent and other well-known ingredients, so that the smooth por-
15 tions of the roll as well as the engraved por-
tions are coated. The paste is then scraped cleanly from the smooth portions with a scraping device called a doctor, leaving the depressions in the roll filled with dye paste.

20 In printing, the cloth is pressed against the prepared roll which rotates at the same speed and in the same direction as the cloth travels. Since the smooth portions of the roll are free from dye paste, these portions
25 will impart no paste to the cloth, but the cloth will pick up the paste retained in the depressions and crevices of the engraved de-
sign. The design of the roll will thereby be continuously transferred to the cloth.

30 The dye pastes offered to the trade for use in printing are dispersions of finely di-
35 vided particles of insoluble dyestuff in wa-
ter and, in general, have a consistency rang-
ing, for example, from that of glycerine to
that of molasses. It is necessary that these
40 pastes, which are used for printing in the
above described manner, shall be absolutely
free from lumps and grit. Especially is
this true of vat dyestuff pastes. Since the
45 rolls are made of soft copper, any grit
present in the dye paste is liable to score
the smooth portions of the roll when scraped
off by the doctor. Any depression in the
50 roll, such as a scratch, even though hairlike,
will become filled with the dye paste when
the roll is coated. When the paste is
scraped off the roll to prepare it for the
printing operation, a bit of dye paste will
remain in such a depression. In printing,
55 this bit of dye paste will be transposed to

the cloth, imparting thereto a blemish in the printed design.

A scratched or scored roll can be repaired only by resurfacing the roll, re-engraving the design thereon and repolishing the sur- 55 face. Such a procedure is expensive.

Since the striations of the engraving are generally fine, it is necessary that the parti-
cles of dye which constitute the paste shall
be small and uniformly dispersed. Such 60 a paste will fill uniformly the striations of
the design in the roll and will be imparted
as an even coating to the cloth in the print-
ing operation. Lumps even as small as a
pinhead are objectionable. Any large lumps 65 present in the dye paste may be scraped out
of the striations of the design, leaving an
uncovered space which will be imparted to
the cloth as a blank. Smaller lumps of
dye which are not uniformly distributed 70
throughout the paste may not be scraped off
by the doctor and consequently will produce
a heavier spot on the finished print, resulting
in uneven dyeing. In dyeing by the pad and
jig method (pigment padding method), it is 75
equally important that the paste be free from
lumps, otherwise dyeings made with such
a paste will show little dark spots and
streaks, due to the heavier dyeing effect of
80 the lumps.

Heretofore, it has been proposed to elimi-
nate lumps and grit from such pastes, by
subjecting them to grinding in a paint mill.
In this way, the grit has been disintegrated
85 into particles too fine to scratch the rolls,
and lumps of dye paste have been broken up.
But the operation of grinding requires large
power consumption, and is exceedingly slow.
With a small outlay for equipment, output
90 is greatly retarded. A large outlay for ap-
paratus is necessary to speed up the capacity
of the grinding operation.

Attempts have also been made to screen
the pastes, by passing them through a vibra-
tory or gyratory screen, of about 200 mesh. 95
However, the pastes are so thick that they
will not flow through the screen when it is
at rest and will scarcely flow through when
brushed across its surface. While some will
100 pass through the screen in motion, this

screening operation is also slow. Also, because of the strain on the cloth, even the strongest screens soon break. A break in the screen necessitates the rescreening of the whole batch, since grit and lumps must be absolutely eliminated.

According to the present invention, it has been found that the grit can be eliminated and lumps can be broken up by directing a stream of the dye paste against a foraminous member, such as a fine screen, preferably at an acute angle to the surface of the member.

This method is to be distinguished from atomizing methods wherein a thin stream of material is sprayed under high velocity against a screen, for the purpose of breaking the material up into a mist. In the present instance, the stream need not necessarily be fine and need not necessarily move under high velocity.

This method is also to be distinguished from the processes wherein material is forced against a screen under a static pressure head. When dye pastes of this type are forced against a screen under a static pressure head, the solid particles act as a filter bed and prevent the paste from passing through. To prevent the screen acting as a filter, it is therefore important that the air pressures on both sides of the screen be substantially equal. One way in which this is ensured is by having the area of the screen greater than the cross section area of the stream of dye paste, and having both sides of the screen exposed to the free atmosphere.

The nature of the invention having been indicated above, it will be apparent that one object thereof is to provide a method of preparing dyestuffs in the form of smooth pastes free from grit or large particles.

Another object is to provide dye pastes which shall print evenly from a printing roll.

A further object is to provide dye pastes which do not scratch the soft copper rolls used in printing cloth with dyes.

A simple form of apparatus suitable for carrying out the process of the present invention, which apparatus is more fully described in the United States Patent No. 1,810,935 of Robert O. Wood and Byron L. West, June 23, 1931, is shown in the accompanying drawing, wherein the figure is a diagrammatic representation of one form of the apparatus. Referring to the drawing, a cylindrical section of pipe 1 of large diameter is closed at one end by a head 2, except for certain openings to be later described.

Within pipe 1 is located a fine metallic screen 3 of, say, 200 mesh. The head 2 is bored and threaded at 4 to receive the vertical pipe 5 through which the material to be screened is introduced. At about right angles to this aperture 4, the head is tapped and threaded at 6 to receive the horizontal

outlet pipe 7, through which the unscreened material is discharged. Intermediate between these apertures, the head is also tapped as at 8, to provide a vent. In operation, a pipe is inserted in this vent to prevent material from splashing out. Screen 3, above mentioned, is welded to an annular disc 9 which, in turn, is held in place in the pipe 1 by means of a cap 10 which is threaded to the pipe 1 at 11.

The process is carried out in the apparatus as follows:

The pipe connection 5 leads the paste from a container (not shown) to a point close to the face of the screen. Velocity is imparted to this paste by subjecting the interior of the container to pressure, or by having the surface of the paste in the container at a higher level than the end of the pipe. In this apparatus, the paste is directed against the screen under a velocity head in excess of that of normal gravity flow of said paste across said screen. The stream of paste sweeps across the screen and fine material and disintegrated lumps pass through the screen and are collected. Coarse material, such as grit and lumps larger than the apertures of the screen, do not pass through but are carried or swept off the surface on the approach side. This coarse material, or run-off, may be collected and recirculated until all the dye lumps have been broken up and have passed through the screen. A residue of grit and foreign matter remaining can be discarded. The pipe 7 serves to carry away the stream of dye paste to be returned to the container for repassage across the screen. The opening 8 insures that the air pressures on both sides of the screen will be substantially equal so that there will be no tendency for the screen to act as a filter. The sweeping and dynamic action of the stream onto and across the face of the screen contributes to break up the lumps present in the dye paste and force the liquid and finely suspended particles through the screen.

A colloid mill may be used in connection with the screening process to homogenize the paste, but it is to be understood that the colloid mill alone does not disintegrate all the grit. The process can be used in the manufacture of pastes of Indanthrene yellow G, Indanthrene blue GCD, Indanthrene violet RR, Indanthrene black B, Indanthrene blue DR, Indanthrene blue BCS, Indanthrene violet R, Indanthrene blue RS, and alizarine.

From a consideration of the above disclosure, it will be readily apparent that the invention is independent of any particular form of apparatus, and that, for this reason, other forms of apparatus may be designed which will operate on the same principle. The size of the interstices of the screen used

will be governed by the use to be made of the screened dye paste. However, it is not intended to cover the screening of dye pastes of all consistencies through screens of all sizes. The invention is limited to the screening of dye pastes, so thick, through screens so fine, that under the static influence of gravity but little material will pass through a horizontal screen. The invention, as defined in the following claims, accordingly is to be construed as limited with regard to the size of the interstices of the screen, and the consistency of the dye paste.

I claim:

15 1. In the process for screening a dye paste which is so viscous through a screen which is so fine that under the static influence of gravity little of the paste will pass therethrough, the improvement which comprises sweeping a body of said dye paste across and in contact with the surface of the screen under the influence of an initial velocity head in excess of that due to normal gravity flow directed at an acute angle to the surface of 20 the screen, and collecting the dye paste which passes through the interstices of the screen.

25 2. The process of screening an aqueous suspension comprising a water-insoluble organic dyestuff in finely divided condition and larger particles of foreign material, which comprises forcibly projecting a stream of said suspension at a velocity in excess of that of normal gravity flow against a foraminous member the openings of which are so fine that under the static influence of gravity little of the suspension will pass therethrough, and collecting the suspension which passes through said member.

30 3. The process of screening an aqueous suspension comprising a water-insoluble organic dyestuff in finely divided condition and larger particles of foreign material, which comprises forcibly projecting a stream of said suspension, at a velocity in excess of that of normal gravity flow against a foraminous member the openings of which are so fine that under the static influence of gravity little of the suspension will pass therethrough, said stream being directed at an acute angle to the surface of said foraminous member and impinging upon an extended effective area of said member, and collecting the suspension which passes through said member.

35 4. The process of screening a dyestuff paste containing grit and comprising an aqueous suspension of a water-insoluble organic dyestuff in finely divided condition, which comprises forcibly projecting a stream of said paste, at a velocity in excess of that of normal gravity flow, against a foraminous member the openings of which are so fine that under the static influence of gravity little of the paste will pass therethrough,

said stream being of smaller cross-sectional area than the area of said member and impinging upon an extended effective area of said member, equalizing the pressure upon both sides of said effective area, and collecting the paste which passes through said member. 70

5. The process of screening a dyestuff paste containing grit and comprising an aqueous suspension of a vat dyestuff in finely divided condition, which comprises forcibly projecting a stream of said paste, at a velocity in excess of that of normal gravity flow, against a screen the openings of which are so fine that under the static influence of gravity little of the paste will pass therethrough, said stream being directed at an acute angle to the surface of said screen and impinging upon an extended effective area of said screen, equalizing the pressure upon both sides of said screen, and collecting the paste which passes through said screen. 75

6. The process of screening a dyestuff paste containing grit and comprising an aqueous suspension of a vat dyestuff in finely divided condition, which comprises forcibly projecting a stream of said paste, at a velocity in excess of that of normal gravity flow, against a screen the openings of which are so fine that under the static influence of gravity little of the paste will pass therethrough, collecting the paste which passes through said screen, and withdrawing and returning for re-screening the paste not passing through said screen. 80 85 90

7. The process of screening a dyestuff paste containing grit and comprising an aqueous suspension of a vat dyestuff in finely divided condition, which comprises forcibly projecting a stream of said paste at a velocity in excess of that of normal gravity flow, against a screen the openings of which are so fine that under the static influence of gravity little of the paste will pass therethrough, said stream being of smaller cross-sectional area than the area of the screen and directed at an acute angle to the surface of said screen and impinging upon an extended effective area of said screen, equalizing the pressure upon both sides of said screen, and collecting the paste passing through the effective area. 100 105 110 115

In testimony whereof I affix my signature.

CERTIFICATE OF CORRECTION.

Patent No. 1,901,275.

March 14, 1933.

ROBERT O. WOOD.

It is hereby certified that error appears in the printed specification of the above numbered patent requiring correction as follows: Page 3, line 77, claim 5, strike out "said" second occurrence; line 115, claim 7, for "screen" read "effective area", and lines 116 and 117, for "effective area" read "screen"; and that the said Letters Patent should be read with these corrections therein that the same may conform to the record of the case in the Patent Office.

Signed and sealed this 16th day of May, A. D. 1933.

(Seal)

M. J. Moore.
Acting Commissioner of Patents.
